UNITED STATES PATENT OFFICE.

LOUIS ROSENBAUM, OF NEW YORK, N. Y.

SAD-IRON.

1,044,820.

Specification of Letters Patent.

Patented Nov. 19, 1912.

Application filed February 2, 1912. Serial No. 674,899.

To all whom it may concern:

Be it known that I, LOUIS ROSENBAUM, a citizen of the United States, residing at the city of New York, borough of Manhattan, State of New York, have invented a certain new and useful Improvement in Sad-Irons, of which the following is a specification, reference being had to the accompanying drawings, forming a part hereof, in 10 which—

Figure 1 is a side elevational view of a sad-iron embodying my invention; Fig. 2 is a rear elevational view of the same; Fig. 3 is a longitudinal sectional view through the 15 same; Fig. 4 is a transverse sectional view through the same; Fig. 5 is a top plan view; Fig. 6 is a top plan view, on a reduced scale, of the lower or base-casting; and Fig. 7 is a top plan view, partly broken away, of 20 a slightly modified form of sad-iron embodying my invention.

This invention relates to a certain new and useful improvement in sad-irons and particularly to that class of sad-irons 25 wherein a combustible fluid is used as the heating medium.

Heretofore sad-irons of the class stated, commonly called gas-irons, have generally, so far as I am aware, been made-up or constructed of a more or less large number of individual or distinct parts connected or secured together in various ways; it has been found, however, that the cost of production of such irons is comparatively heavy and 35 that they more or less quickly get out of good working order.

The objects of my present invention are to provide a sad-iron of the kind stated which has but few, practically the minimum 40 number of, separate parts, and thereby reduce materially the number of joints and practically to a minimum the liability of leakage of the combustible fluid; to provide a sad-iron of the kind stated, 45 which may be readily manufactured and at reduced cost, which is efficient in operation, in which the several parts may be easily and quickly assembled and readily fastened or connected operatively together, and which 50 will not easily get out of good working order, and to improve generally upon sad-irons of the class mentioned.

With these objects in view, my invention resides in the novel construction, arrangement, and combination of the several parts

of my new sad-iron, all as will hereinafter be described and afterward pointed out in the claims.

As shown in the accompanying drawings, wherein like reference characters refer to 60 like parts throughout the several views, my new iron comprises preferably but two separate castings—a lower or body-portion or base-casting, as I will call it, A, and an upper or handle-portion casting, as it might 65 be termed, B.

The lower or body-portion A is preferably a hollow metallic casting having a bottom wall 1 of any suitable thickness, flat on its outer or ironing surface, preferably longitudinally corrugated or grooved on its inner surface, as at 1^a, and preferably pointed at its forward end, as at 1^b, and having the shape in plan elevation of the usual iron. Base-casting A at its rear is 70 also preferably cut away or provided with an opening, as at 2, and with a pair of inwardly-disposed or projecting shoulders 2^a, the greater part of its top wall being also 75 preferably cut-away, as at 3, continuously with said opening or cut-away portion 2 in the rear wall thereof, as shown particularly in Fig. 6 and for purposes hereinafter more fully appearing.

The side wall of casting A preferably comprises, as shown particularly in Fig. 4, portions 4 and 5. Portion 4 extends preferably and substantially perpendicularly upwardly from the outer edge of bottom wall 1, while portion 5, which lies within the area of portion 4, extends convergently or obliquely upwardly therefrom and is preferably integrally connected at its lower end to the upper end of portion 4 by means of a web or the like 6 having preferably a curved 85 outer surface or face, as shown. Web-portion 6 is also preferably cut-away, as shown, to provide a series of elongated draft-openings or slots 7 around said base-casting, while depending from said side-wall-portion 90 5 is a series of flat vertically-disposed aprons or curtains 8 substantially parallel with said side-wall-portion 4 and coincident, respectively, with said slots 7, whereby, as it might 100 be said, said slots 7 open or lead directly upwardly from the interior of casting A. At the forward end 1^b of casting A, said web-portion 6 is preferably further provided with a draft-opening 9, and at the forward end of casting A, said side-wall-portion 105 110

tion 5 is also preferably provided adjacent the upper end thereof with a pair of oppositely-disposed draft-openings 10, as shown particularly in Figs. 1, 3, and 4. In its top 5 and at the forward end thereof, casting A is also preferably provided with an enlarged draft-opening 11 separated from said cut-away portion 3 by means of a bridge-portion 12, as shown particularly in Fig. 6, upon which bridge-portion 12 is preferably integrally formed an upstanding threaded boss 13, for purposes hereinafter more fully appearing. Projecting upwardly from, and 10 preferably integral with, said side-wall-portion 5 is a portion 14 which extends substantially completely along one, preferably the left-hand, side of casting A and for a short distance, and at the forward end of the iron, on the right-hand side thereof, said portion 14 being preferably thickened at its rearward and forward ends, as at 15 and 16, respectively, and cut-away at the forward part 15 of casting A and on opposite sides thereof, as at 17, as shown particularly in Figs. 1, 3, and 4. At its right-hand upper rear end, 20 said side-wall-portion 5 is also provided with an upstanding portion or handle-support 18, the upper face of said support 18 being on the same horizontal plane with the upper face of said portion 14, as shown particularly in Figs. 1 and 2. As shown particularly in Fig. 2, the base or lower side of the open or cut-away rear end wall of casting A is preferably corrugated or scalloped, as at 25 19. Upper or handle-portion casting B comprises a handle-plate 20 adapted to extend completely over the top of casting A and to rest upon said upwardly-projecting handle-supporting portion 14 and said handle-support 18, as shown particularly in Fig. 30 1. Extending upwardly at one, preferably the forward, end of, and preferably cast integrally with, handle-plate 20, is a handle-arm 21; and extending somewhat obliquely upwardly and rearwardly from said handle-plate 20 at its other, or rear, end, and also 45 preferably cast integrally therewith, is what I term a hot air and gas reservoir or chamber 22 provided in its upper end, as at 22^a, with a combustible fluid supply opening and 50 fully described in United States Letters Patent No. 904,087, granted to me November 17, 1908. Extending upwardly and inwardly from and adjacent the upper end of, and 55 also preferably cast integrally with, said reservoir or chamber 22, and in proper alinement with the upper end or portion of handle-arm 21, is a short handle-arm 23, the upper ends of said handle-arms 21 and 60 23 being oppositely cut-away or recessed or provided with oppositely-disposed horizontal slots 21^a and 23^a, respectively, for receiving and holding a through-bolt 24 adapted to support a suitable handle 25, as shown 65 particularly in Figs. 1 and 3. On its under

side and communicating with said reservoir or chamber 22, said handle-plate 20 is integrally provided with a throat or neck portion 26 leading into, and integral with, an elongated hollow burner 27 extending substantially parallel with handle-plate 20 and having on its under face a plurality of jet-perforations or openings 27^a, burner 27 being adapted to fit longitudinally within casting A and of a length as to extend from the rear end of casting A to closely adjacent the forward end thereof, as shown particularly in Fig. 3.

As shown particularly in Fig. 3, said throat or neck-portion 26 is preferably gradually enlarged or flares outwardly from said handle-plate 20 toward its mouth or toward said burner 27, the front wall thereof being preferably obliquely-disposed or curving gently forwardly relatively to handle-plate 20, whereby there is provided a gradually increasing passage for, and one free from any sharp angles or projections which might interfere with or impede, the flow of the combustible fluid from chamber 22 to burner 27. The rear end of burner 27 is integrally provided with, and closed by, a flat or plate portion 28 having a shape substantially as shown in Fig. 2 adapted to fit in, and to the greater extent close, the open rear end of casting A, and to engage with said shoulders 2^a, said corrugations or scallops 19 therebeneath providing further draft-openings into the interior of casting A. A hand-guard 29 of any suitable material is preferably arranged above handle-plate 20 and between handle-arms 21 and 23 with its opposite ends secured, as shown, on said through-bolt 24. In operatively assembling said castings A and B, casting B is first placed at the rear end of casting A with burner 27 directed into the interior of casting A and the forward end of handle-plate 20 slightly above, or resting upon, said support 18 and thickened portion 15 of said portion 14, and is then slidably moved forwardly on, or relatively to, casting A until said plate or flat portion 28 fits neatly in, and substantially flush with, the rear end of casting A. When in such position, the forward portion of burner 27 will lie beneath said bridge portion 12 and said plate 28 will engage with said shoulders 2^a and said castings A and B be thereby loosely held together, and whereby also said castings A and B may now, in the preferred form of my new iron, be firmly fastened or secured together by means of a single screw or the like 100 passing through handle-plate 20 into said threaded boss 13. It will be noted that said cut-away portion 3 in the top wall of casting A provides a space adapted to permit free movement of said throat or neck portion 26 when the said castings are being operatively assembled, and which is, for the 105 110 115 120 125 130

greater part or approximately, taken up or closed thereby when said castings are assembled. The flame of the ignited combustible fluid supplied to burner 27 through chamber 22 and throat or neck portion 26 and issuing from said jet-openings 27^a is directed downwardly from the burner directly upon the corrugated inner face of bottom wall 1 of casting A, and said cut-away portions 17 in said portion 14 and the open space between said handle-support 18 and the thickened forward end 16 of said portion 14 provide escape passages to the exterior for the products of combustion arising from the interior of casting A through said top opening 11 and cut-away portion 3.

By corrugating or grooving the inner face of bottom wall 1 of casting A, I am enabled to present to the flame of the heating medium or combustible fluid nearly twice the area of heating surface that is obtained with a flat face. The iron being usually grasped and manipulated by the right-hand of the user, it will be seen that said upwardly-projecting portion 14 prevents the products of combustion arising from casting A coming directly in contact with the clothes of the user. This portion 14 may, of course, be cast on the right-hand side of casting A for left-hand users. The said elongated slots 7 and also said draft-openings 9 and 10 provide means for a plentiful supply of air to promote practically perfect combustion of the combustible fluid supplied to the burner; and it will be noted that said curtains or aprons 8 absolutely prevent any escape laterally of the flame or products of combustion of the burning combustible fluid, to the possible injury of the user of the iron or the goods being operated upon.

I have found my new iron to be highly efficient in operation, and from the foregoing it will be seen that my new iron comprises but two, practically the minimum number of, castings, and that the same may be quickly and easily operatively assembled and secured together and will not readily get out of good working order.

In Fig. 7 I have shown a slightly modified form of sad-iron embodying my invention. In this form, instead of providing casting A with a single boss 13, I provide the same with a plurality of such bosses and removably secure castings A and B operably together by a plurality of screws 30^a, handle-plate 20 being preferably cut-away or recessed, as shown, on its opposite sides, as at 20^b, for receiving said screws.

I am aware that minor changes in the construction, arrangement, and combination of the several parts of my new iron might be made and substituted for those herein shown and described without departing from the nature and principle of my invention.

Having thus described my invention, what I claim and desire to secure by Letters Patent is:

1. The combination, in a sad-iron, of a hollow base-casting having an opening in its rear wall and its top wall partly cut-away continuously with said opening, and an upper casting integrally comprising a handle-plate, an elongated burner extending substantially parallel with said handle-plate and having a plurality of jet-perforations on its under face, and a neck portion between said handle-plate and burner, said handle-plate being adapted to fit on top of said base-casting, said burner being adapted to fit longitudinally within said base-casting, and said cut-away portion in the top wall of said base-casting being adapted to accommodate said neck portion; substantially as described.

2. The combination, in a sad-iron, of a hollow base-casting having an opening in its rear wall and its top wall partly cut-away continuously with said opening, and an upper casting integrally comprising a handle-plate, an air and gas chamber on the upper side of said handle-plate, an elongated burner below, and extending substantially parallel with, said handle-plate and having a plurality of jet-perforations on its under face, and a neck portion between said handle-plate and burner and communicating with said burner and said chamber, said handle-plate being adapted to fit on top of said base-casting, said burner being adapted to fit longitudinally within said base-casting, and said cut-away portion in the top wall of said base-casting being adapted to accommodate said neck portion; substantially as described.

3. The combination, in a sad-iron, of a hollow base-casting having an opening in its rear wall and its top wall partly cut-away continuously with said opening and provided with a plurality of handle-plate supports extending above its top wall and having their upper faces on the same horizontal plane, and an upper casting integrally comprising a handle-plate, an air and gas chamber on the upper side of said handle-plate, an elongated burner below, and extending substantially parallel with, said handle-plate and having a plurality of jet-perforations on its under face, and a neck portion between said handle-plate and burner and communicating with said burner and said chamber, said handle-plate being adapted to rest on said handle-plate supports, said burner being adapted to fit longitudinally within said base-casting, and said cut-away portion in top wall of said base-casting being adapted to accommodate said neck portion; substantially as described.

4. The combination, in a sad-iron, of a hollow base-casting having an opening in its

rear wall and its top wall partly cut-away continuously with said opening and provided with a plurality of handle-plate supports extending above its top wall and having their upper faces on the same horizontal plane, an upper casting integrally comprising a handle-plate, an air and gas chamber on the upper side of said handle-plate, an elongated burner below, and extending substantially parallel with, said handle-plate and having a plurality of jet-perforations on its under face, and a neck portion between said handle-plate and burner and communicating with said burner and said chamber, said handle-plate being adapted to removably rest on said handle-plate supports, said burner being adapted to removably fit longitudinally within said base-casting, and said cut-away portion in the top wall of said base-casting being adapted to removably accommodate said neck portion, and means adapted to removably secure said base and upper castings operatively together; substantially as described.

5. The combination, in a sad-iron, of a hollow base-casting having an opening in its rear wall and its top wall partly cut-away continuously with said opening and provided on its top wall with an upstanding boss and with a plurality of handle-plate supports extending above its top wall and having their upper faces on the same horizontal plane, an upper casting integrally comprising a handle-plate, an air and gas chamber on the upper side of said handle-plate, an elongated burner below, and extending substantially parallel with, said handle-plate and having a plurality of jet-perforations on its under face, and a neck portion between said handle-plate and burner and communicating with said burner and said chamber, said handle-plate being adapted to removably rest on said handle-plate supports, said burner being adapted to removably fit longitudinally within said base-casting, and said cut-away portion in the top wall of said base-casting being adapted to removably accommodate said neck portion, and a screw adapted to pass through said handle-plate into said boss to removably secure said base and upper castings operatively together; substantially as described.

6. A sad-iron base or body portion consisting of a hollow metallic casting having a bottom wall, a top wall, and a side wall, said side wall comprising a portion extending for a short distance substantially perpendicularly upwardly from said bottom wall, a portion within the area of said perpendicular portion and extending obliquely upwardly therefrom to said top wall, and a web connecting the lower end of said oblique portion and the upper end of said perpendicular portion and cut-away to provide a series of

elongated draft-slots around said casting; substantially as described.

7. A sad-iron base or body portion consisting of a hollow metallic casting having a bottom wall, a top wall, and a side wall, said side wall comprising a portion extending for a short distance substantially perpendicularly upwardly from said bottom wall, a portion within the area of said perpendicular portion and extending obliquely upwardly therefrom to said top wall, a web connecting the lower end of said oblique portion and the upper end of said perpendicular portion and cut-away to provide a series of elongated draft-slots around said casting, and a series of curtains or aprons depending from said oblique side-wall-portion substantially parallel with said perpendicular side-wall-portion and coincident with said draft-slots; substantially as described.

8. An upper casting for sad-irons integrally comprising a handle plate, an elongated burner extending substantially parallel with, and below, said handle-plate and having a plurality of jet-perforations on its under face, and a neck-portion between said handle plate and burner, said neck portion being located adjacent one end of said handle plate and leading into one end of, and gradually flaring outwardly from said handle plate toward, said burner; substantially as described.

9. An upper casting for sad-irons integrally comprising a handle plate, an air and gas chamber on, and extending upwardly from one end of, said handle plate, an elongated burner below, and extending substantially parallel with, said handle plate and having a plurality of jet perforations on its under face, and a neck portion between said handle plate and burner, said neck portion being located adjacent one end of said handle plate and leading at one end into said chamber and at its other end into one end of, and gradually flaring outwardly from said handle plate toward, said burner; substantially as described.

10. The combination, in a sad-iron, of a hollow base casting cut away at its rear and provided with a pair of inwardly-disposed shoulders and in its top wall partly cut away continuously with said cut-away portion of the rear thereof, an upper casting comprising a handle-plate, an elongated burner extending substantially parallel with said handle-plate and having a plurality of jet-perforations on its under face, a neck-portion between said handle-plate and burner, and a flat plate portion at the rear of said burner, said handle-plate being adapted to fit on top of said base casting, said burner being adapted to fit longitudinally within said base casting, said cut away portion in the top wall of said base casting being adapted to accommodate said neck portion,

and said flat plate portion being adapted to fit in the cut away portion at the rear of said base casting and loosely engage with said shoulders, and means adapted to fasten 5 said castings operatively together; substantially as described.

In testimony whereof, I have signed my

name to this specification, in the presence of two subscribing witnesses.

LOUIS ROSENBAUM.
